UNITED STATES PATENT OFFICE.

VINCENZO BONZAGNI, OF BOSTON, MASSACHUSETTS.

PIPE AND FLUE CONNECTION.

SPECIFICATION forming part of Letters Patent No. 365,783, dated July 5, 1887.

Application filed November 23, 1886. Serial No. 219,728. (No model.)

To all whom it may concern:

Be it known that I, VINCENZO BONZAGNI, of Boston, in the county of Suffolk and State of Massachusetts, have invented certain improvements in Stove and other Pipe and Flue Connections, of which the following is a full, clear, and exact description, reference being had to the accompanying drawings, making part of this specification, in which—

10 Figure 1 is a section through a chimney-flue with a thimble and stove-pipe collar applied thereto in accordance with my invention; Fig. 2, a perspective view of a thimble to be permanently located in the passage of the chimney-flue; Fig. 3, a perspective view of a plate and stove-pipe collar, preferably formed integral; Fig. 4, a plate with its ventilating device. Fig. 5 shows the application of my invention to gas or lamp burners, &c.; Fig. 6, an 20 elevation of a plate constructed in accordance with this invention, and to be applied to the thimble shown in Fig. 2.

To avoid the annoyance and delay incident to the ordinary means of fitting stove-pipes to chimney-flues is the chief purpose of this invention, which consists in two principal features associated together—to wit, a thimble of fixed and unvarying size to be permanently located in each chimney-flue and a series of 30 stove or furnace pipe collars or plates having openings of different diameters—i. e., the opening in one collar or plate being of a diameter different from the opening in another plate or collar—so that pipes of different diameters may be accommodated by using different plates or 35 collars, every one of the plates outside being of the same size and exactly corresponding to that of the seat or place intended for its reception within the thimble in the flue, by which 40 construction and arrangement, when a person wishes to put up a stove, it is only necessary to obtain at the shop one of the collars or plates having the pipe-opening therein corresponding in diameter to that of the pipe to be fitted, 45 and after having placed it over the pipe to enter the plate within the thimble in the flue for its reception, the outside of any plate for a small pipe collar or opening being of the exact size as the outside of a plate having a larger 50 pipe collar or opening, and adapted to snugly fit into and be secured, by screws or otherwise,

to the thimble in a convenient and expeditious manner.

My invention also consists in a pipe of smaller diameter connected with a cap located over a lamp or gas burner, in combination with and leading to a plate having an opening to receive said pipe, and secured within the thimble or chimney-flue, whereby the smoke and foul air and gases are carried out of the apartment.

In the said drawings, A represents a section of a chimney-flue, within the passage a of which, leading to an apartment, (not shown,) is located a metallic or soapstone thimble or casing, B, having a flange, b, extending around its outer edge, which incloses a recessed seat, c, for a rectangular plate, C, of corresponding size, which fits snugly therein, preferably flush with the outer surface of the flange b. This thimble is provided with a large central hole, d, of a diameter always sufficient to receive the largest size, as well as the smallest size, of stove or furnace pipe employed, said central hole being of a size sufficient also to receive a tubular section, e, of any size, when one is employed, at the back of the plate C, for the purpose of providing a more extended bearing for the pipe where it enters the hole c of the thimble B. The front of the plate C may be provided or not with a collar, h; but as it imparts a finished appearance to the plate, and also materially strengthens the union thereof with the tubular section e, I prefer to employ it, and it may be made separate from or integral with the plate C. Near the corners of the plate, and also at corresponding points in the recessed seat c, countersunk holes i are formed for the passage of screws, by which the plate may be held in place.

Were the thimbles used in chimney-flues all of the same size—i. e., each having a recessed seat of the same unvarying size to receive any number of plates C of the same unvarying size outside as the seat of each thimble, so as to snugly fit therein or thereon, and with different-sized openings for different-sized pipes, and were each thimble also provided with a central opening, d, large enough to accommodate a stove or furnace pipe of any size—it would be an extremely simple operation to fit any pipe into a chimney-flue, for the reason that were

the pipe five inches in diameter a plate there-
for having an opening of five inches could be
obtainable at the stove-shop, which would be
sure to fit the thimble C. So, likewise, if the
5 pipe to be fitted were five and one-half inches or
six inches in diameter, a plate having an open-
ing of either five and one-half inches or six
inches could be purchased and a snug and per-
fect connection made with great facility. The
10 flange b at the outer edge of the front of the
thimble may be dispensed with and the plate
bear on the outer surface of the thimble, care
being taken, however, that the screw-holes i in
the thimble and those i in the plates be directly
15 in line or register with each other. Should
the stove or other pipe be removed from the
chimney-flue, a ventilator, D, similar to that
shown in Fig. 4, may be placed within the seat
e of the thimble, the size of the outside of the
20 ventilator-plate being of the same size as the
outer edge of the seat, so as to exactly fit
therein. I prefer to cast the plate C, its tubu-
lar section e, and its collar h in one and the
same piece, as thereby they can all be handled
25 and fitted in position at one operation. I may,
however, cast the tubular section e and plate
C together, and apply the collar as a separate
piece to the pipe.

To rid an apartment of the smoke and dis-
30 agreeable and impure odors proceeding from
lamp and gas burners, I resort to the follow-
ing-described arrangement: Immediately over
the burner k is located a cap, G, which has an
opening in its top, and is connected with a
35 small pipe, l, supported by a bracket, F, from
the side of the room. The opposite end of the
pipe l enters a hole, m, of corresponding size
formed in a plate, C, screwed within the seat
c of the thimble, as before described, this pipe,
40 besides relieving the room of the smoke and foul
odors and gases, also conducting away any

objectionable heated air which may be gener-
ated in the room from the gas or oil when burn-
ing.

I am aware that a stove-pipe thimble con-
sisting of an outer case substantially square
in cross-section and fitting into the aperture
from an apartment into the flue, and a cubi-
form case fitting snugly within said outer case
and having in its side walls openings for stove-
pipes of different sizes, is old, such a construc-
tion being illustrated in United States Patent
No. 34,743, to W. W. Davis, dated March 25,
1862; and hence I disclaim such earlier device.

I claim—

1. The herein-described removable chimney-
flue thimble having a portion adapted to ex-
tend into a flue and an exposed face, which
latter has an aperture, d, therein, in combina-
tion with a perforated plate, C, removably
60 attached to the exposed face of said thimble,
the perforation in plate C being smaller than
aperture d, substantially as set forth.

2. The herein-described stove-pipe thimble
B, it having formed in its outer face an aper-
ture, d, and being provided with a flange, b,
surrounding said plate, whereby there is formed
a recess, e, in combination with a perforated
plate, C, adapted to be seated in said recess,
substantially as set forth.

3. The plate C, a tubular section, e, extend-
ing through said plate, and a strengthening-
flange, h, between said plate and tubular sec-
tion, said flange being cast integrally with the
plate and tube-section, substantially as set
75 forth.

Witness my hand this 19th day of November,
1886.

VINCENZO BONZAGNI.

In presence of—

N. W. STEARNS,
H. W. STEARNS.
